PRESSURE SENSOR

George Wintress, Carversville, Pa.

Filed Dec. 19, 1958, Ser. No. 781,727

7 Claims. (Cl. 200—83)

This invention relates to apparatus for determining fluid pressure of a predetermined limit. The invention is intended for use with control equipment and more especially with equipment that stops the operation of a machine if a pressure rises to a certain value.

It is an object of the invention to provide improved apparatus for sensing pressure above a predetermined limit, and to provide a very simple and reliable device for the purpose, the device being capable of operating at very high fluid pressures.

The pressure sensing apparatus of this invention employs a diaphragm with edge sealing, a center electrical contact and mechanical loading of the diaphragm at angularly spaced locations around the center close enough together to maintain a relatively even distribution of the loading around the center.

Other objects, features, and advantages of the invention will appear or be pointed out as the description proceeds.

In the drawing, forming a part hereof, in which like reference characters indicate corresponding parts in all the views:

FIGURE 1 is a vertical sectional view of a pressure sensor made in accordance with this invention; and

FIGURE 2 is a sectional view on the line 2—2 of FIGURE 1.

The construction illustrated includes a lower housing 10 having its lower outside surface formed with threads 11 for screwing into an opening from which the pressure fluid is to be supplied. A conduit 12 extends axially through the bottom of the lower housing and communicates with a chamber 14 in the housing. There is a lip 16 surrounding the upper end of the conduit 12.

An O-ring 18 fits into an annular groove 20 around and adjacent to a side wall 22 of a recess in the top of the lower housing 10. A diaphragm 24 extends across the chamber 14 and rests on the lip 16 and the O-ring 18. The lower housing 10 and the diaphragm 24 are preferably made of metal and the circumference of the diaphragm contacts firmly with the side wall 22 of the metal of the lower housing. Spring steel is particularly good material for the diaphragm.

An insulator 26 extends across the upper end of the lower housing 10 and is preferably of the same overall cross-section so that the outside surface of the insulator 26 is flush with the outside surface of the lower housing 10. The bottom wall of the insulator has a cylindrical shoulder 28 which fits snugly into the recess provided by the side wall 22; and the bottom of the shoulder 28 contacts with the top of the diaphragm 24 to hold the diaphragm down against the O-ring 18.

The bottom surface of the insulator 26 inward from the shoulder 28 rises progressively toward the center of the insulator and provides a dome ceiling for the chamber 14. Thus the insulator 26 is an intermediate portion of the housing and forms the top of the chamber 14. The insulator 26 has a flat annular surface 30 extending radially outward from the shoulder 28 and this annular surface contacts with a corresponding and confronting surface 32 on the lower housing 10.

A contact holder 34 fits with a press fit into an axial bore 36 through the insulator 26. This holder 34 has a bottom surface forming a continuation of the dome-shaped surface of the insulator, and the holder 34 is actually the center portion of the insulator. Both the in-

2

sulator 26 and the contact holder 34 are made of electrical insulating material and preferably plastic. A metal contact 40 is located at or near the center of the contact holder 34 and projects for some distance below the immediately surrounding surface at the top of the chamber 14.

At angularly-spaced locations around the contact 40, and radially spaced from the contact 40, there are a plurality of loading pins 42 extending through cylindrical openings in the contact holder 34. These pins 42 are preferably made of electrical insulating material, such as Bakelite, and they have a running fit in the opening through which they extend. The lower ends of the pins 42 contact with the top surface of the diaphragm 24; and the upper ends of the pins 42 bear against a plate 44 in the lower end of a guide-way 46 in an upper housing 48.

Bores 50 at angularly spaced locations around the upper housing 48 have shoulders 52 at an intermediate level and there is a screw 54 in each bore with a head that bears against the shoulder 52, and a shank that extends through openings 56 in the insulator 26 and that threads into other openings 58 in the lower housing 10. The bores 50 and openings 56 are not threaded. The screws 54 attach the upper housing 48 to the lower housing 10 with the insulator 26 firmly clamped between them.

The plate 44 is pressed down against the pins 42 by a spring 60 located in the guideway 46, and there is a nut 62 at the upper end of the spring 60. A screw 64 threads through the nut 62 and extends downwardly inside the coils of the spring 60 which serve to hold the screw 64 in a generally centered position. The upper end of the screw 64 contacts with a top wall 66 of the upper housing 48. There is an opening 68 through the top wall 66 above the end of the screw 64 but of smaller cross section than the screw 64. A screw driver can be inserted through the opening 68 to engage a slot in the upper end of the screw 64. As the screw 64 is turned in one direction, it moves the nut 62 downward and adds to the compression of the spring 60. The upward reaction of the spring 60 is transmitted through the nut 62 the screw 64 to the top wall 66 of the upper housing. Thus the screw 64 provides a means for changing the pressure of the spring 60 against the plate 44, and the resulting downward force of the pins 42 against the diaphragm 24.

There is a set screw 70 in one side of the nut 62 for preventing relative rotation of the nut 62 and screw 64 after the tension of the spring has been adjusted to a desired value. Rotation of the nut 62 and screw 64 as a unit will not change the pressure of the spring 60; and with the set screw 70 tight, the nut 62 and screw 64 turn as a unit if either one of them turns.

A conductor 72 leads from the center contact 40 and through a passage in the insulator 26 to a location outside of the apparatus for connection with a load circuit such as control equipment.

In the operation of the invention, fluid under pressure is supplied to the conduit 12, but the fluid is prevented from entering the chamber 14 by the diaphragm 24 which seats firmly against the lip 16. The diaphragm thus serves as a valve element for preventing flow of fluid past the lip 16. The force of the spring 60 holds the diaphragm 24 against the lip 16, this force being transmitted to the diaphragm through the plate 44 and pins 42.

If the fluid pressure in the conduit 12 rises high enough to force the diaphragm 24 away from the lip 16, then fluid enters the chamber 14 under the diaphragm and contacts with a large area of the diaphragm and forces it upwards quickly into contact with the top of the chamber 14. The pins 42 are raised and the diaphragm touches the center contact 40 to close an electric circuit to the conductor 72. The metal lower housing 10 and the metal diaphragm 24 are part of the electric circuit.

Fluid under the diaphragm 24 thrusts the O-ring 18 outwardly against the side wall 22 and into the corner where the diaphragm 24 meets the side wall 22 so that no fluid can escape into the part of the chamber 14 above the diaphragm. Even if fluid could escape around the edges of the diaphragm, however, no gas pressure could build up on the top side of the diaphragm because the pins 42 have a running clearance in the openings through the contact holder 34 and this provides for escape of gas along the pins. The upper housing 48 above the contact holder 34 is open to the atmosphere.

The preferred embodiment of the invention has been illustrated and described. Terms of orientation are, of course, relative; and changes and modifications can be made, and some features can be used in different combinations without departing from the invention as defined in the claims.

What is claimed is:

1. A pressure sensor comprising a housing having a chamber therein, an electric circuit, a diaphragm comprising a part of the electric circuit, said diaphragm being in the chamber and forming a partition across the chamber dividing the chamber into upper and lower portions, a conduit extending through the housing and opening into the lower portion of the chamber below the diaphragm, an electrical contact in said circuit and located in the upper portion of the chamber and confronting the diaphragm across an unobstructed space of the chamber, resilient loading means exerting force against the diaphragm to hold the diaphragm down and spaced from said contact, the diaphragm being movable upwardly far enough to touch the contact and constituting part of an electric circuit, and means for controlling the degree of fluid pressure required under the diaphragm to move the diaphragm into position to touch said contact.

2. A pressure sensor comprising a housing having a chamber therein, a diaphragm in the chamber and forming a partition across the chamber dividing the chamber into upper and lower portions, a conduit extending through the housing and opening into the lower portion of the chamber below the diaphragm, an electrical contact in the same chamber with the diaphragm but in the upper portion of the chamber, resilient loading means upper portion of the chamber, exerting force against the diaphragm to hold the diaphragm down and spaced from said contact, the diaphragm being movable upwardly far enough to touch the contact and constituting part of an electric circuit, and means for controlling the degree of fluid pressure required under the diaphragm to move the diaphragm into position to touch said contact, and in which the housing is of composite construction and there is an element made of electrical insulating material forming at least a part of the top of the chamber and the contact is carried by the insulating element, and there is a conductor extending through the insulating material from said contact.

3. A pressure sensor comprising a housing having a chamber therein, a diaphragm in the chamber, a conduit extending through the housing and opening into the chamber below the diaphragm, an electrical contact in the chamber above the diaphragm, resilient loading means holding the diaphragm down and spaced from said contact, the diaphragm being movable upwardly far enough to touch the contact and constituting part of an electric circuit, and means for controlling the degree of fluid pressure required under the diaphragm to move the diaphragm into position to touch said contact, the housing being of composite construction with an element of electrical insulating material forming at least a part of the top of the chamber, and with the contact carried by the insulating element, a conductor extending through the insulating material from said contact, and in which the resilient loading means includes a plurality of pins extending through holes in the insulating material and for some distance above the upper termination of the insulating material, the holes being at angularly-spaced loca-

tions around the contact, a plate in contact with the upper ends of the pins, and a spring loading said plate.

4. The pressure sensor described in claim 3, and in which the pins are at angularly spaced locations around the circumference of a circle and the contact is at the center of the circle.

5. A pressure sensor comprising a housing having a chamber therein, a diaphragm in the chamber and forming a partition across the chamber dividing the chamber into upper and lower portions, a conduit extending through the housing and opening into the lower portion of the chamber below the diaphragm, an electrical contact in the same chamber with the diaphragm but in the upper portion of the chamber, resilient loading means exerting force against the diaphragm to hold the diaphragm down and spaced from said contact, the diaphragm being movable upwardly far enough to touch the contact and constituting part of an electric circuit, and means for controlling the degree of fluid pressure required under the diaphragm to move the diaphragm into position to touch said contact, and in which the chamber has a dome-shaped top, and a seat at the end of the conduit, the diaphragm being held in contact with the seat to limit the area of the diaphragm which is exposed to the pressure in the conduit.

6. A pressure sensor comprising a housing having a chamber therein, a diaphragm in the chamber and forming a partition across the chamber dividing the chamber into upper and lower portions, a conduit extending through the housing and opening into the lower portion of the chamber below the diaphragm, an electrical contact in the same chamber with the diaphragm but in the upper portion of the chamber, resilient loading means exerting force against the diaphragm to hold the diaphragm down and spaced from said contact, the diaphragm being movable upwardly far enough to touch the contact and constituting part of an electric circuit, and means for controlling the degree of fluid pressure required under the diaphragm to move the diaphragm into position to touch said circuit, and in which there is an O-ring located in a depression in the bottom wall of the chamber under the peripheral portion of the diaphragm.

7. A pressure sensor comprising a housing having a lower portion with a threaded end for screwing into a pressure connection, an upper portion connected to the lower portion by clamping screws and with an insulating element clamped between the upper and lower portions of the housing, a chamber within the housing formed between recessed areas of confronting faces of the lower portion of the housing and the insulating element, a metal diaphragm within the chamber and forming a partition across the chamber, an annular recess in the lower wall of the chamber around the circumference of the chamber for holding an O-ring which seals the diaphragm against leakage of fluid around the edges of the diaphragm, the lower portion of the housing having a center conduit leading into the chamber under the diaphragm and opening through a boss in the bottom wall of the chamber, the boss having end faces against which the diaphragm seats to prevent escape of fluid from the passage, a spring carried by the upper portion of the housing; a plate against which the spring presses, pins located at angularly spaced regions around a circle and extending through the insulating element and into contact with the top of the diaphragm for transmitting the pressure of the spring to the diaphragm, an electrical contact on the top wall of the chamber in position to be touched by the diaphragm when pressure under the diaphragm exceeds the pressure transmitted from the spring through the pins, and means for adjusting the pressure of the spring.
